UNITED STATES PATENT OFFICE.

CHARLES R. MURRAY, OF SAN FRANCISCO, CALIFORNIA.

THERMO-ELECTRIC SWITCH.

1,187,083.

Specification of Letters Patent. Patented June 13, 1916.

Application filed December 1, 1913. Serial No. 804,050.

To all whom it may concern:

Be it known that I, CHARLES R. MURRAY, a citizen of the United States, residing at San Francisco, in the county of San Francisco and State of California, have invented a new and useful Thermo-Electric Switch, of which the following is a specification in such full and clear terms as will enable those skilled in the art to construct and use the same.

This invention relates to a heat operated circuit closing switch used for the purpose of indicating the location of a fire in buildings or vessels.

15 An object of the invention is to provide a fixture which is capable of being placed in an out of the way position and which is provided with means to protect the working parts thereof.

20 Another object of the invention is to provide a device which may have the fuse easily renewed when it happens to be burned out or injured from any cause.

Another object of the invention is to provide 25 a switch which is capable of being repaired or examined without removing the switch casing from the ceiling or wall.

An embodiment of the invention is shown 30 in the drawing in which the same reference numeral is applied to the same portion throughout, but I am aware that there are many modifications thereof.

Figure 1 is a central, vertical, sectional view of the complete switch, and Fig. 2 is a 35 bottom plan view of the device with a portion of the mica covering broken away for purposes of illustration.

The numeral 1 indicates a metal cylinder closed at its upper end and outwardly flanged 40 at its lower end to form a wider cylinder 2, the latter cylinder having an outwardly extending flange 3. The wider cylinder has a mica disk 4 secured thereto by means of screws 6, 7, 8, and 9, the screws 6 and 7 also holding a fuse 5 in place. The fuse is flat and has slots 5' and 5'' at its ends to facilitate replacement. Within the lower end of 45 the cylinder 1 is a flanged fiber block 10, screws 11 and 12 holding it in place. Binding posts 13 and 14 are secured to the under side of the fiber block, and suitable wires 14'

and 15 extend therefrom to suitable electrical apparatus. Wires 16 and 17 extend through the fiber block, and are electrically connected with the contact points 18 and 19. 55 Slidable within the block is a fiber rod 20 on the upper end of which is a metal block 21. This block has a light spring 22 bearing thereon to prevent the plunger from hammering on the fuse 5 when the device is used aboard ship.

In use the switch is installed in a hole bored in the ceiling of the room or compartment of the vessel and whenever a fire occurs the fuse 5 will melt at such a temperature as it is desired to notify the indicator board. It will be observed that the small plunger and fiber rod are entirely supported by the fuse strip 5, the hole being provided in the mica plate for that purpose. As soon 70 as the fuse is burned out the weight of the plunger causes it to make the contact by closing the circuit at contact points above the fiber block.

Having thus described my invention what 75 I claim as new and desire to secure by Letters Patent of the United States, is as follows, modifications within the scope of the claim being expressly reserved:

A thermo alarm switch comprising a casing having a small chamber joined to a larger, flatter chamber, a flanged insulating bushing in the lower part of the smaller chamber and removable therefrom through the larger chamber, electric contacts, a metal plunger movable in the smaller chamber and having a depending rod extending through the insulating bushing to the electric contacts carried by the insulating bushing and which the plunger may connect, a spring on 90 the top of the plunger, a mica cover for the casing through which the plunger rod passes, and a fusible metal strip extending across the outside of the casing cover for supporting the plunger and rod connected thereto. 95

In testimony whereof I have hereunto set my hand November, A. D. 1913, in the presence of the two subscribed witnesses.

CHARLES R. MURRAY.
